UNITED STATES PATENT OFFICE.

BALUS M. PIKE, OF GADSDEN, ALABAMA.

DESIGN FOR A HAME-TUG.

SPECIFICATION forming part of Design No. 28,430, dated March 29, 1898.

Application filed October 30, 1897. Serial No. 656,973. Term of patent 7 years.

To all whom it may concern:

Be it known that I, BALUS M. PIKE, a citizen of the United States, residing at Gadsden, in the county of Etowah and State of Alabama, have invented a new and original Design for a Hame-Tug, of which the following is a specification.

This invention relates to a new and original design for a hame-tug; and it has for its object to provide a design of this character that shall be both useful and ornamental.

The leading feature of the design resides in an elongated body having a flat base-plate provided with parallel side flanges projecting from one side thereof and having a series of segmental scallops and flat cross-bars connecting said parallel flanges at the angular points between the scallops.

A minor feature of the design resides in the base-plate having rounded ends, rounded studs projected therefrom in planes between the cross-bars, and an offstanding hook-shaped figure at one end.

In the drawings, Figure 1 is a perspective view of a hame-tug embodying the herein-described design. Fig. 2 is a plan view thereof.

Referring to the accompanying drawings, the numeral 1 designates an elongated flat base-plate provided with rounded ends 2 and parallel side flanges 3. The parallel side flanges 3 are projected from the same side of the plate 1 and are provided with a series of segmental scallops 4, and the said side flanges 3 are connected at the angular portions between the scallops by a series of parallel flat cross-bars 5. The flat base-plate 1 is further provided with rounded studs 6, projected from one side thereof in planes between the cross-bars 5, and with a hook-shaped figure 7, projected from one end thereof.

What I claim is—

The design for a hame-tug herein shown and described.

In testimony that I claim the foregoing as my own I have hereto affixed my signature in 45 the presence of two witnesses.

BALUS M. PIKE.
